UNITED STATES PATENT OFFICE.

WILLIAM H. WALKER, OF CHICAGO, ILLINOIS.

PHONE INDEX AND GUIDE.

Application filed January 21, 1922. Serial No. 530,909.

To all whom it may concern:

Be it known that I, WILLIAM H. WALKER, a citizen of the United States, residing at Chicago, in the county of Cook and State 5 of Illinois, have invented a certain new and useful Improvement in Phone Indexes and Guides, of which the following is a specification.

My invention relates to additional memorandum leaves for directories, and particularly to an alphabetical set of memorandum leaves for insertion into telephone directories, which serve at the same time as a convenience for the users thereof and as 10 15 an advertising medium. Further objects of my invention will appear from time to time in the course of the specification.

My invention is illustrated more or less diagrammatically in the accompanying 20 drawings, wherein—

Figure 1 is a plan view of one page of my device, with parts broken away;

Figures 2 and 3 are plan views of modified forms with parts broken away;

25 Figure 4 is a section on the line 4—4 of Fig. 1;

Figure 5 is a partial end view of Fig. 2;

Figure 6 is a section on the line 6—6 of Fig. 2;

30 Figure 7 is a partial end view of Fig. 3;

Figure 8 is a section on the lines 8—8 of Fig. 3.

Like parts are indicated by like symbols throughout the drawings and specifications.

35 A is a memorandum page, the center A¹ of which is taken up with a convenient memorandum space, herein illustrated as a space for putting down names and telephone numbers frequently used by the user 40 of the directory. The surrounding space A² is preferably covered with advertising material. The drawings illustrate only one memorandum page but such a page is preferably provided for each letter of the 45 alphabet, to be inserted at the head of that letter in the directory. If the space for names and numbers is not sufficient, one or more slips or additional pages may be pasted thereover at top or side.

50 The alphabetical set of pages is preferably made and supplied complete for insertion in the directory, and it is desirable that the entire set be in some way fastened together and fastened to the book. This 55 may be done in a variety of ways, and I have illustrated diagrammatically three

main types. Figs. 1 and 4 illustrate pages along the rear edge of which is pasted a tape or flap B, which engages either side of the edge and incloses a wire B¹, or any other suitable reinforcement, running from end to end of the page. The tapes are shown with extending ends B², which may, if desired, be made sufficiently long to be tied at the back of the directory, as at B³, or may be otherwise secured in any satisfactory way.

Figs. 2, 5 and 6 illustrate a form wherein in the pages, reinforced by wire C as aforesaid, are provided with projecting wire ends, which engage any suitable top and bottom frame elements, for example the plates C¹. In Fig. 6 the wire is illustrated as penetrating or riveted through the plate, as at C², but obviously any other form of attachment might be used. The wires are spaced apart on these plates by approximately the thickness of that letter of the alphabet in the directory which comes between the two pages, thus permitting the wire and page for A to be inserted at the head of letter A, and the wire and page for B to be inserted at the letter B, with all pages of the directory of letter A lying between them. The side elements and the cross wires form, in effect, a gridiron through which the pages of the directory pass. The entire assembly may be kept in place in the directory by any suitable securing means, such as the tapes C³, illustrated in Fig. 2 as tied together at the back 90 of the directory. Obviously the pages might be secured to the directory in many other ways, for example by wire clips.

In Figs. 3, 7 and 8 a form is shown wherein the wires terminate at each end in loops D, through which pass pins D¹. The loops and pin at the upper corner of the page are permanently joined and may be spaced in any suitable way, for example by substituting a cylinder D² instead of a simple eyelet at the end of each wire. The set of pages is then inserted into the directory by swinging them consecutively into place at the appropriate position and then threading the pin through the eyelets or cylinders at the lower corner of the page. This pin may be fastened in place by any suitable means, and may have, for example, a head D³, a screw-threaded end D⁴, and a nut D⁵ secured thereto to complete the assembly. The pages may be kept in place in the directory, for example, by the tapes 100 105 110

D⁶, which join the pins at each end of the page assembly, but any other suitable means, of course, might be used.

This set of pages forms an ideal advertising medium which may be inserted into any directory. The user of the directory writes at the head of each letter of the alphabet his most frequent calls, and therefore is constantly referring to that page.

10 About the edge of it is placed advertising material, which is thus constantly beneath the eyes of the user of the directory.

While I have illustrated a working device and forms of reinforcing and fastening these 15 pages into the book, it will be obvious that many changes might be made in the number, size, shape, relation and disposition of parts without departing from the spirit of my invention; and particularly I do not wish 20 to limit myself to the specific forms herein illustrated.

I claim:

1. An insertion for directories comprising a plurality of alphabetical memorandum 25 pages, means for securing them permanently together as a unit, and a reinforcing element along the inner edge of each page.

2. An insertion for directories comprising a plurality of alphabetical memorandum 30 pages, means for securing them permanently together as a unit, and a reinforcing element along the inner edge of each page comprising a wire and means for securing it to the page.

3. An insertion for directories comprising a plurality of alphabetical memorandum pages, and means for securing them permanently together as a unit, comprising reinforcing means along the inner edge of each page and means for connecting said reinforcing means.

4. An insertion for directories comprising a plurality of alphabetical memorandum pages, and means for securing them permanently together as a unit, comprising reinforcing means along the inner edge of each page and means for connecting said reinforcing means at the top and bottom of all the pages.

5. An insertion for directories comprising a plurality of alphabetical memorandum pages, and means for securing them to the directory, and a reinforcing element along the inner edge of each page.

6. An insertion for directories comprising a plurality of alphabetical memorandum pages, means for securing them permanently together as a unit and for securing the unit to the directory, each page being provided with a form for setting down names and numbers frequently called and beginning with the letter of the index page upon which they are positioned.

Signed at Chicago, county of Cook, and State of Illinois, this 18th day of January, 65 1922.

WILLIAM H. WALKER.
